VALVE FOR FIRE EXTINGUISHER SYSTEMS.

No. 558,259.

Patented Apr. 14, 1896.

UNITED STATES PATENT OFFICE.

EMANUEL MANEY COOK, OF INDIANAPOLIS, INDIANA.

VALVE FOR FIRE-EXTINGUISHER SYSTEMS.

SPECIFICATION forming part of Letters Patent No. 558,259, dated April 14, 1896.

Application filed July 8, 1895. Serial No. 555,240. (No model.)

To all whom it may concern:

Be it known that I, EMANUEL MANEY COOK, a citizen of the United States, residing at Indianapolis, in the county of Marion and State 5 of Indiana, have invented certain new and useful Improvements in Valves for Fire-Extinguisher Systems; and I do hereby declare the following to be a full, clear, and exact description of the invention, such as will enable 10 others skilled in the art to which it appertains to make and use the same.

My invention relates to the main valve of an automatic sprinkler system of the so-called "dry-pipe" class.

15 The object of the mechanism constituting the invention is to prevent the flow of water from the main supply-pipe to the distributing-pipes so long as all the sprinkler-heads remain closed and to permit such flow immediately any one of said sprinkler-heads is 20 opened.

The invention consists in the construction and combination of parts hereinafter described and claimed.

25 In the drawings, Figure 1 is a central vertical section of the main valve, its operating mechanism, and casing. Fig. 2 is a horizontal section on line 2 2 of Fig. 1, the cone *n* and its nut *n'* being removed. Fig. 3 is a vertical section of the right side of the casing and the valve-stem *E* and the device employed for closing the valve *C* before the compressed air is pumped into the chamber.

30 Referring to the parts by letters, *A* represents the main-valve chamber, which is enclosed by a casing *a*. The inlet to the chamber is through the cylindrical opening *a'*, with which in use the main supply-pipe is connected, and the outlet is through the opening 35 *a''*, with which the main distributing-pipe is connected.

35 *B* represents an air-chamber, which is enclosed by a casing *b*. The two casings *a* and *b* are preferably secured together, and the 40 two chambers communicate through the opening of port *b'*. This communicating port *b'* is closed by a disk-valve *C*, which when it has been drawn against its seat *b''* is there held by pressure of air within said chamber.

45 *B*. *b''* represents pins fixed to the casing *b* and entering holes *b'* in the valve, the purpose of said pins being to guide the valve in

its movement squarely against or away from its seat.

The inlet to chamber *A* is closed by a valve 55 *D*, which is cylindrical upon its under side, and this cylindrical part *d* fits the cylindrical opening *a'*. Above the part *d* is an annular horizontal flange *d'*, which is adapted to be held down against a finished seat *a''* and thereby act as a disk-valve to completely close the inlet-opening.

A valve-stem *E* is attached to the middle of the valve *C*. It extends horizontally across the chamber *A*, and its end enters and slides 65 in the guide *e*, which is secured to the valve-casing *a*. This stem is made in parts *e' e''*, the approximate ends of which are threaded and connected by a turnbuckle *e''*. The part *e''* is broadened, and in this broadened part 70 a slot *e'* is formed.

A valve-stem *G* is attached to the middle of the upper side of the valve *D* and extends vertically therefrom, passing through the slot *e'*, and its upper end passes through a guide 75 *g*, which is fastened to the casing *a*. A second stem *g'* is preferably secured to the under side of said valve and passes through a hole in the guide *g''*, which is secured to the casing *a*.

80 Upon the two stems *E* and *G* are the relatively adjustable inclines *J* and *N*, adapted to engage with each other in substantially the manner shown, whereby the upward pressure of the water upon the valve *D* tends to push 85 the incline *J*, with the result of transmitting pressure through the stem *E* against the valve *C* in opposition to the air-pressure therein in the chamber *B*. In the best construction known to me, which is shown in the drawings, 90 the inclines *J* and *N* are formed and then relative adjustment is provided for in the manner as follows: The end of the slot *e'* next to the valve *C* is beveled upward away from said valve forming the incline *J*. On the valve-stem *G* is a movable cone *n*, on the upper end of which is the incline *N*, the angle of which is complementary to the angle of the incline *J*. This cone is adjusted by means of the nut *n'*, which may be screwed up and down upon 100 the threaded stem *G*.

In order to make a more secure and firmer contact between the inclines *J* and *N* and to diminish the effect of the strain upon the

stems E and G, I also bevel the end of the slot e^4 from the top downward and away from said valve C, forming the incline J' , and I mount upon the stem G above stem E a second cone n^2 , the incline N' of which is the complement of the incline J' , with which it is adapted to engage. A nut n^3 , which is adjustable upon the threaded stem, is provided, so that the cone n^2 may be moved down into engagement 10 with the incline J' .

A hand-hole f , which may be closed by a plate F, is made in the casing a and it is through this hand-hole that the parts within the casing may be adjusted. In the casing 15 at the end of the stem E a hole h is formed, which hole is normally closed by a plate II, bolted across it; but when it is desired to adjust the parts both plates F and II are removed. An extension-piece K is screwed onto 20 the end of the stem E. A nut l , which screws onto the piece K, bears against the casing a. As this nut is screwed out the stem E is drawn to the right, thereby pulling the valve C against its seat. The valve D is then closed. 25 The cones n and n^2 are adjusted up and down, respectively, to bring the inclines N N' into contact with the inclines J J' , which latter inclines may also be adjusted by means of the turnbuckle e^3 . Of course the water is shut 30 off in the main supply-pipe during this operation. The chamber B and the distributing-pipe system is now filled with compressed air by the usual means, and preferably through the pipe L, which is connected in said distributing system, whereupon the valve C is held against its seat by the air-pressure in 35 chamber B. The extension K may now be removed from the stem E, and both of the plates F and II may be bolted to the casing a over the holes f and h .

A check-valve M, of any suitable construction, is placed either in the outlet of chamber A or in the main distributing-pipe, whereby the air in the distributing-pipes is prevented from entering the chamber A. In the 45 particular construction shown this valve is a disk, which is seated by the air-pressure above it against an annular seat in the outlet-opening a^2 . The end of the valve-stem G enters 50 a socket m in the under side of said valve, whereby the opening of the valve D causes the valve M to be opened.

When the water is turned onto the main, it 55 presses against valve D; but the upward movement of said valve is resisted because of the engagement of the inclines J and N, and the movement of the incline J out of the path of incline N is resisted by the pressure in chamber B against valve C; but when this 60 air-pressure is relieved—as, for example, by the opening of any sprinkler-head—the valve C may be opened, and will be opened by the pressure of the incline N against the incline J. When the valve C has been opened, as 65 shown in dotted lines in Fig. 1, the incline J has moved out of the way of the incline N, whereupon the valve D is opened wide by the

water from the main, as shown by dotted lines in said figure. The water flows through the casing a, filling the distributing-pipes and 70 discharging in the usual manner through the open sprinkler or sprinklers.

Having described my invention, I claim—

1. The combination of a chamber A adapted for connection in the water-supply pipe of an 75 automatic sprinkler system, an air-chamber B communicating with chamber A, and a pipe for connecting chamber B with the distributing-pipe system, with a valve for the inlet to the chamber A, a valve for closing the communication between the two chambers, valve-stems secured to said valves respectively, and relatively-adjustable inclines carried by said valve-stems and adapted to engage with each other, substantially as and for the purpose 85 specified.

2. The combination of a chamber A adapted for connection with the supply-pipe of an automatic sprinkler system, an air-chamber B communicating with chamber A, and a pipe, 80 connecting chamber B with the distributing system, with a valve adapted to close the inlet to chamber B, a valve-stem secured to said valve, and extending across the chamber A, means for guiding said stem, a valve for closing the communication between said two chambers, a valve-stem secured to said valve, lying substantially at right angles to the valve-stem first named, and composed of two parts which are adjustably connected, an incline secured to one of said parts which is remote from the valve, an adjustable incline, upon the valve-stem first named, which inclines are adapted to engage with each other, and means for guiding the two-part valve-stem, substantially as and for the purpose 95 specified.

3. The combination of a chamber A adapted for connection with the supply-pipe of an automatic sprinkler system, an air-chamber B, 100 communicating with chamber A, and a pipe connecting chamber B with the distributing-pipe system, with a valve for closing the communication between said chambers, a valve-stem secured thereto having a longitudinal 105 slot with a beveled end, a valve for closing the inlet to chamber A, a valve-stem secured to said valve and passing through said slot, an incline adjustable upon the last-named stem and adapted to engage with the beveled end 110 of said slot, and devices for engaging with said stems and guiding them, substantially as and for the purpose specified.

4. The combination of a chamber A, adapted for connection in the supply-pipe of an automatic sprinkler system, an air-chamber B communicating with chamber A, and a pipe connecting the said air-chamber with the distributing system, with a valve for closing the communication between said chambers, a 115 valve-stem connected with said valve and having a longitudinal slot, two oppositely beveled surfaces at one end of said slot, a valve for closing the inlet to chamber A a valve 120

stem secured thereto and two cones adjustable upon the valve-stem last named and adapted to engage with said beveled surfaces, and devices for guiding said stems, substantially as and for the purpose specified.

5. The combination of a chamber A adapted for connection with the supply-pipe of an automatic sprinkler system, an air-chamber communicating with the chamber A, and a pipe connecting the air-chamber with the distributing-pipe system, with a valve for closing the communication between said chambers, a valve-stem secured to said valve and composed of two parts, a turnbuckle for connecting said parts, a slot in the part remote from the valve and two oppositely-beveled surfaces at the end of said slot, a valve for closing the inlet to chamber A, a valve-stem secured thereto, two cones adjustable upon said stem and adapted to engage with said beveled surfaces, and two yokes secured within the chamber A engaging with the ends of said valve-stems respectively, substantially as and for the purpose specified.

25 6. The combination of a casing inclosing a chamber A, and adapted for connection in the supply-pipe of an automatic sprinkler sys-

tem, a casing b secured to casing a and inclosing an air-chamber B, said casings having an opening through which the said chambers 30 may communicate; the casing a having also an opening opposite to the opening through which the chambers communicate, and also a hand-hole through which the mechanism within chamber A may be reached, with a 35 valve for closing the communication between said chambers, a valve-stem secured thereto having a threaded end, a yoke for guiding said stem, a part K adapted to screw onto the end of said stem, a nut adapted to screw onto said 40 device and to bear against the outside of casing a, a valve for closing the inlet to chamber A, a valve-stem secured thereto, relatively-adjustable beveled surfaces carried by said two stems and adapted to engage with each other, 45 and a yoke for guiding the last-named stem, substantially as and for the purpose specified.

In testimony whereof I affix my signature in presence of two witnesses.

EMANUEL MANEY COOK.
